Inventor:

Lewis F. Betts

United States Patent Office.

LEWIS F. BETTS, OF CHICAGO, ILLINOIS.

Letters Patent No. 81,585, dated September 1, 1868.

IMPROVED CAN-TOP.

The Schedule referred to in these Letters Patent and making part of the same.

TO ALL WHOM IT MAY CONCERN:

Be it known that I, LEWIS F. BETTS, of the city of Chicago, in the county of Cook, and State of Illinois, have invented a new and useful Improvement in Can-Tops; and I do declare that the following is a full, clear, and exact description of the same, reference being had to the accompanying drawings, making part of this specification, in which—

Figure 1 is a top view.

Figure 2, a reverse view.

Figure 3, a transverse section.

Figure 7, a transverse section, with the portion B removed.

Figures 4, 5, 6 represent a modification of the same plan reduced in size, and adapted to oil or other cans having contracted tops.

Like letters refer to like parts in all the figures.

The object of my invention is to so construct the tops of cans for fruit and other uses, that the same can be more easily and securely made air-tight.

To enable others skilled in the art to make and use my invention, I proceed to describe its construction and operation.

A is the outer portion of the cover, which is to be permanently fastened to the body of the can in the usual manner. This portion is provided with a shoulder, b, and with two cam-like projections, a, one on each side of the inner edge, and so arranged that the broad parts are opposite each other. This portion A is cut from any suitable metal in the ordinary manner; then stamped in any desired manner, forming the shoulder b; the cam-like projections are then turned down, as shown in fig. 7. This portion is also provided with holes or openings, c, to receive the lugs d.

The central portion of the cover, which is removable, is cut and stamped in the usual manner, and may be of the form shown in fig. 3, being provided with a rim or band, which, when this portion is in place, rests upon the shoulder b. It is provided with lugs, d, corresponding in number and position with the openings c. A bar or handle, f, is also attached, the ends of which pass through the cover and form the lugs d. In use, a ring of rubber, or other suitable material, is laid upon the shoulder b, the lugs d are inserted into the top or cover by means of the handle f, the central portion of the cover B is turned around, and the lugs d passing under the cam-like projections a, the cover is pressed tightly against the rubber, and the can will be air-tight. This portion of the cover can at any time be easily removed without injury, and can be used again and again as long as the can lasts.

I also construct covers for kerosene-oil and other cans, to be used without rubber, operating on the same principle as the covers above described, as shown in figs. 4, 5, 6. That part of this cover or top marked A is provided with cam-like projection, a, as before described, and is to be permanently attached to the can. This part also has openings to receive the lugs d. The removable portion may have the form shown in fig. 6, and is provided with lugs, d, and handle, f, and the whole is operated in the same manner as the cam-top first described, except that it may be used without rubber, though, if desired, it can be constructed so as to be used with rubber. In this form or modification the handle passes through the curved or bent portion of the top or cover as in the other, so that I am enabled to attach to thin metal, strongly and securely, both handle and lugs, and get a sufficient pressure for clamping-purposes without displacing the lugs, which might be the case if they were simply soldered on to sheet metal, thus making a cheap and efficient top for air-tight or closed cans.

Having fully described my invention, what I claim as new, and desire to secure by Letters Patent, is—

1. The inclines or cams a, when burred or turned down so as to form the cam on the edge of the metal of which the breast or permanent portion of the top is constructed, and operating substantially as specified.
2. The handle f, when projecting through the removable top or cover B, so that its ends will form the lugs or pins d, substantially as described.
3. The permanent portion of the top or breast A, provided with the cams or inclines a, in combination with the removable portion or cover B and lugs or pins d, substantially as and for the purposes specified.

LEWIS F. BETTS.
